MACHINE FOR OPERATING ON SHOES

Herman A. Imhof, Beverly, Mass., assignor to
 United Shoe Machinery Corporation, Flemington, N. J., a corporation of New Jersey

Application April 17, 1951, Serial No. 221,482

26 Claims. (Cl. 12—10.3)

1

This invention relates to machines for use in operating on shoes, and more particularly, to lasting machines of the type disclosed in United States Letters Patent No. 2,201,866, issued May 21, 1940, in the name of Robert H. Lawson, certain portions of which are shown and described in more detail in United States Letters Patent No. 1,854,204, issued April 19, 1932, also in the name of Robert H. Lawson. It is to be understood, however, that certain features of this invention are not limited to use in lasting machines or to embodiment in machine organizations of the exact kind exemplified in these prior patents.

Machines of the kind disclosed in the aforementioned patents are provided with a jack for supporting a shoe and for feeding it, step by step, relatively to a pair of lasting units each including a gripper for tensioning the upper materials and a fastening-inserting mechanism comprising an overlaying member, and means for driving fastenings therethrough to secure the lasting margin of the tensioned upper materials in lasted position, in different locations from breastline to tip line along the opposite side of the bottom of the shoe, progressively, during a plurality of successive operating cycles of the lasting units. Before the sidelasting operation is performed, the shoe is pulled over and the upper materials, adjacent to the toe end of the last and back to the vicinity of the tip line, are secured by tacks driven into the last, in locations adjacent to the marginal edges of the shoe bottom, at the extreme end of the toe, just in front of the tip line and, in some cases, also just to the rear of the tip line. As the lasting operation proceeds from breastline to tip line, it sometimes happens, during an operating cycle of the lasting units, that the overlaying members, as they are advanced over the shoe bottom prior to the driving of fastenings therethrough, strike these pulling-over tacks, or some of them, and either push these tacks farther into the last or bend them over, thus rendering it quite difficult to remove these tacks at a later stage in the manufacture of the shoe.

One object of this invention is to provide in machines of this general type and having a pair of devices for operating progressively, along the opposite sides of the bottom of a shoe, means for removing fastenings previously inserted into the shoe and thereby eliminating difficulties of the kind mentioned above. With this object in view, and in accordance with a feature of the invention, the lasting devices of the herein illus-

trated machine are each provided with a member operable to remove fastenings previously inserted into the shoe, in locations adjacent to the marginal edges of the shoe bottom, during the operation of the machine. More particularly, each of these lasting devices, or units, is provided with a tack-pulling member operable to remove fastenings from the shoe together with mechanism for rendering these tack-pulling members operative during predetermined operating cycles of the lasting units. The mechanism for rendering the tack-pulling members operative may include a cam, rotated in time relation to the feeding movements of the jack and so shaped as to effect operation of these members during those operating cycles when the lasting units are operating in the vicinity of the tip line of the shoe. To facilitate their actions, these tack-pulling members are mounted for movements in directions extending heightwise and transversely of the shoe bottom, and such movements are imparted, respectively, to these members by wire-feeding mechanisms, associated with fastening-inserting mechanisms of the lasting devices, and the overlaying members already mentioned. The mechanism for rendering the tack-pulling members operative includes means, controlled by the aforementioned cam, for connecting these members to elements of the wire-feeding mechanisms which move in directions extending heightwise of the shoe bottom and means are provided for elevating the tack-pulling members to positions well above the bottom of the shoe, during those operating cycles of the lasting units when these members are disconnected from these vertically moving elements. To avoid possible damage to the parts, which might result if the tack-pulling members, or either of them, were prevented from completing their movements transversely of the shoe bottom, yielding connections are provided between these tack-pulling members and the overlaying members of the lasting devices which, as already pointed out, impart such transverse movements thereto.

To avoid pulling up portions of the upper materials which have been tensioned during the pulling-over operation and secured by the pulling-over tacks, in the vicinity of the tip line of the shoe, the machine disclosed in the patent to Lawson No. 2,201,866 is provided with mechanism for rendering the gripper jaws of each of the lasting units inoperative to close on the upper materials during predetermined operating cycles of these units. Also, to avoid possible interference of these jaws with the upstanding por-

tions of the upper materials; as the jack feeds the shoe, means including a control cam are provided for reducing the extent of downward movements of the gripper jaws by decreasing the downward movements of the gripper-actuating members, during those operating cycles when the gripper jaws are inoperative. The mechanism for rendering the gripper jaws inoperative includes latch members associated with the gripper-actuating members and adapted to connect the gripper jaws to the actuating members, thereby preventing the closing of these jaws, which is effected as a result of relative movement between the jaws and the actuating members, when the extent of downward movement of these members is reduced, during predetermined operating cycles of the lasting units. When complete downward movements are imparted to these actuating members, during all other operating cycles of the units, these latch members are rendered ineffective by engagement with fixed stop pins associated with the units.

However, in the machine of the Lawson patent, the actuating members are moved upwardly, first to close the gripper jaws on the upper materials and then to cause these jaws to apply tension thereto, through mechanism which is adapted to yield when a predetermined pull has been applied by these jaws. As the lasting operation approaches the tip line of the shoe, in which vicinity the upper materials have previously been tensioned, the resistance to further tensioning may be so great that the gripper jaws, after closing on the upper materials, are moved upwardly only a very short distance, or not at all. Thus, during the next succeeding operating cycle of the lasting units in which the downward movements of the gripper-actuating members are reduced, the gripper jaws may not be opened or, if opened, the latch members will not be rendered ineffective by engagement with the fixed stop pins mentioned above. In the first case, the upper materials still gripped by the jaws of the grippers will be distorted, or torn, during the next feeding movement of the jack while, in the second case, the gripper jaws will close on the upper materials during the next operating cycle and, since the downward movements of the actuating members are reduced even more in this cycle, will remain closed when the shoe is fed along by the jack, with the aforementioned undesirable results.

It is, therefore, another object of this invention to provide improved means for rendering the gripper jaws of a machine of this type inoperative, during those operating cycles which occur when the lasting units are operating in the vicinity of the tip line of a shoe, which is effective and certain in operation regardless of whether or not the resistance to further tensioning of the upper materials has prevented, or limited, upward movement of the gripper jaws. With this object in view, in the herein illustrated machine the stop pins, heretofore fixed, are mounted for movements in directions away from engagement with the latch members and means, controlled in part by the mechanism for rendering the tack-pulling members operative and in part by the operation of the fastening-inserting drivers, is provided for imparting such movements to these pins. More particularly, when the tack-pulling members are rendered operative, springs associated with these shafts are placed under tension, rotation thereof being at this time prevented by detent members arranged to en-

gage links also connected to these shafts. These detents are adapted to be tripped, thereby to release these shafts to the action of the springs when the fastening-inserting drivers are operated, during the next succeeding operating cycle of the units. Thus, when the gripper-actuating members are moved downwardly in that operating cycle, the stop pins will have been displaced well below their normal positions in which they would have engaged the latch members, and regardless of the heightwise position of the gripper jaws these latch members will be rendered effective.

Further to assure that these latch members will certainly connect the gripper jaws to their actuating members and thereby render these jaws inoperative to close on the upper materials, the cam which controls the extent of downward movement of the gripper-actuating members is so modified that these actuating members are moved downwardly to the full extent during the aforementioned operating cycle, after the stop pins have been displaced as above explained, and before the beginning of the next succeeding operating cycle, this cam effects an upward movement of the gripper-actuating members. As the gripper-actuating members are thus moved upwardly, the gripper jaws remain open since they have previously been connected to these actuating members by the latch members which were rendered ineffective as a result of the downward displacement of the stop pins. Preferably, and in the herein illustrated machine, the cam which is associated with the mechanism for rendering the tack-pulling members operative is so shaped that these members operate during the last three operating cycles of the lasting units while the gripper jaws are rendered inoperative and the downward movements of the gripper-actuating members reduced, thereby to maintain the open gripper jaws well above the upper materials, during the last two operating cycles of the lasting units.

The above and other objects and features of the invention will be set forth in the following detailed description of the embodiment illustrated in the accompanying drawings, and will be pointed out in the claims.

In the drawings,

Fig. 1 is a view in side elevation of a lasting machine embodying the features of the invention;

Fig. 2 is a view in side elevation and at an enlarged scale of a portion of the machine shown in Fig. 1;

Fig. 3 is a view in side elevation showing a portion of the lasting unit which appears on the left in Fig. 2, with certain parts omitted, and others broken away, to simplify the disclosure;

Figs. 4 and 5 are views in front elevation of a portion of the lasting unit which appears on the right in Fig. 1, these views illustrating the parts in different positions assumed during the operation of the machine and with certain other parts omitted to simplify the disclosure;

Fig. 6 is a view, in section, substantially on line VI—VI, of Fig. 4 and looking in the direction of the arrows;

Fig. 7 is a view in side elevation of the lasting unit which appears on the right in Fig. 2 as seen from its opposite side, with certain parts in section and others omitted to simplify the disclosure; and

Figs. 8 and 9 are views in side elevation of a portion of the lasting unit which appears on the

left in Fig. 2 as viewed from the opposite sides thereof, with certain parts in section and others broken away.

Referring to these drawings, and particularly to Figs. 1 and 2 thereof, the lasting machine therein illustrated is similar to that disclosed in the Lawson Patent No. 2,201,866, referred to above, but is provided with fastening-inserting mechanisms of the type disclosed in United States Letters Patent No. 2,418,140, issued on April 1, 1947, in the names of Charles A. Robinson and Herman A. Imhof. Thus this machine has a jack 20 for supporting a shoe and for feeding it relatively to a pair of lasting units, indicated generally by the reference characters 22, 22. These lasting units are mounted on and are operated by mechanism contained within a head casting 24 which is supported upon a column 26 of suitable height, Fig. 1. Each of the two lasting units are of identical construction and comprise similar operating elements, these units, however, being mirror images of each other, as will be apparent from Fig. 2. Hence, the corresponding elements of each unit are identified by similar reference characters and, in the following detailed description, reference to either one of the units will be considered as applying to the other.

Each of the lasting units comprise a housing 100 with which there are associated an anvil 102, gripper jaws 104, 106, and a fastening-forming and inserting mechanism including an overlaying member or nozzle 108, these several elements being constructed in the same manner, and operated by means of mechanism which is the same as that disclosed in the aforementioned patents to which reference may be made for such details as are not herein described. Associated with each of the lasting units is a plunger 110 which is arranged to be reciprocated, by means of a slide 112, in predetermined time relation to the operation of the lasting units for actuating mechanism for feeding wire to the fastening-forming and inserting mechanisms. The wire-feeding mechanism and the means for reciprocating these two plungers is similar to that provided in the machines disclosed in the aforementioned patents and is described in more detail in the Lawson Patent No. 1,854,204, referred to above. As will be readily understood from an examination of the aforementioned patents, the lasting machine so far described is arranged to operate in different locations, from breastline to tip line, along the opposite sides of a shoe supported on the jack 20, progressively, in a plurality of operating cycles, the upper materials, indicated by the reference character U, in each location being seized and tensioned over the last L by the gripper jaws 104, 106, wiped in over the bottom of the shoe and feather of the insole I by the overlaying members 108, and secured in lasted position by fastenings driven through the lasting margin of the upper materials and insole rib R and clenched against the anvils 102.

Prior to the side-lasting operation, the shoe is, of course, pulled over and the upper materials adjacent to the toe end of the last and back to the tip line secured to the insole by means of tacks, one at the extreme end of the toe, two on each side of the shoe just ahead of the tip line and, in some instances, one on each side of the shoe just to the rear of the tip line. As already suggested, to avoid pulling up the upper materials thus previously tensioned and secured to the insole by these tacks, the machine illus-

trated in the Lawson Patent No. 2,201,866 is provided with means for rendering the gripper jaws 104, 106 of each lasting unit inoperative during the last two operating cycles of the machine, while the last two pairs of upper fastenings are driven through the nozzles, or overlaying members, 108. It frequently happens, however, as these nozzles are advanced over the shoe bottom, prior to the driving of the fastenings, that they strike the pulling-over tacks, or some of them, and either push these tacks further into the last, or bend them over, thus rendering the subsequent tack-pulling operation much more difficult to perform. To avoid such difficulty, as well as to eliminate a separate tack-pulling operation, the herein illustrated machine is provided with means for removing the pulling-over tacks located adjacent to the tip line.

Referring to Figs. 1 to 6 of the drawings, each of the lasting units is provided with a tack-pulling rake, indicated generally by the reference character 200. Each of these rakes comprises an enlarged head 202 formed on the lower end of an arm 204 which is pivotally mounted, by means of a pin 206, in a bifurcated slide member 208, Figs. 4 and 5. These slide members are mounted for vertical reciprocation in guideways formed in brackets 210 which are secured to the housings 100 of the lasting units. The heads 202 are cut away at 212 to receive a plurality of fingers 214 which are backed up by a rubber cushion block 216, Fig. 6, and held in place by means of a clip 218 and bolts 220, Figs. 4, 5 and 6. Each of the slide members carries, at its upper end, a trunnion block 222 which is embraced by the bifurcated end 223 of an arm 224, pivotally mounted on a stud 226 that is secured to a portion of the bracket 210, Figs. 4 and 5. Pivoted to each of the arms 224 is a latch member 228 formed with a recess 230 and an elongated slot 232. Also mounted on each of the studs 226 is a bell-crank lever 234 having a downwardly extending arm 236 and a rearwardly extending arm 238, Fig. 2. Fixed in the arm 236 of each of these bell-crank levers is a pin 240 which projects into the slot 232 in one of the latch members 228.

The arm 238 of each of the bell-crank levers 234 carries a block 242, Fig. 2, to which there is secured one end of a Bowden wire 244, housed within a casing 246. At their opposite ends, these Bowden wires are connected to an arm 248 which is pivotally mounted on the outside of the head casting 24, Fig. 1. The arm 248, in turn, is connected by a link 250 to one arm of a bell-crank lever 252, mounted near the lower part of the column 26. The other arm of this bell-crank lever carries a cam roll 254 which is held in engagement with the periphery of a cam 256 by means of a coil spring 258. This cam is adjustably secured, by means of a clamp screw 260 which passes through an arcuate slot 262 therein, to a disk 264 which is secured on the projecting end of a pattern cam shaft 266, corresponding to the pattern cam shaft 12 of the machine described in Lawson No. 2,201,866. On its peripheral surface, the cam 256 is provided with two dwell portions 268, 270 separated by a rise portion 272 and an abrupt drop-off 274.

As shown in Figs. 2, 5 and 5, the plungers 110 which operate the wire-feeding mechanisms are associated with the brackets 210 and each of these plungers is provided with a stud 280 which projects outwardly therefrom. When the cam roll 254 on the bell-crank lever 252, Fig. 1, is in

engagement with the dwell portion 268 of the cam 256, the latch members 228 are swung to positions corresponding to that illustrated in Fig. 5, through the action of the Bowden wires 244, bell-crank levers 234, pins 240 and elongated slots 232. However, as this cam roll travels down the drop-off portion 274 onto the dwell portion 270, these latch members will be swung into positions corresponding to that illustrated in Fig. 4 with the studs 280 engaging the latch members in the recesses 230 therein, thus connecting the slides 208 to the plungers 110. Now, when these plungers are reciprocated to operate the wire feed mechanisms, in a manner explained more particularly in the patent to Lawson No. 1,854,204, the slides 206 and tack-pulling rakes 200 will be moved up and down therewith. As is explained in the Lawson Patent No. 2,201,866, the lasting units are operated twelve times as the lasting operation proceeds from the breastline to the tip line of a shoe supported and fed along by the jack 20 and, during the latter portion of each operating cycle the pattern cam shaft 266 is rotated one twelfth of a turn. The cam 256 is so disposed angularly with respect to the pattern cam shaft 266 that the cam roll 254 travels along the dwell portion 268 of the cam 256, and the slides 208 are disconnected from the plunger 110, during the first nine operating cycles of the machine. When the pattern cam shaft 266 is rotated one twelfth of a turn during the latter part of the ninth operating cycle, this cam roll travels down the drop-off onto the dwell 270, thus connecting the slides 208 to the plungers 110 for reciprocations thereby during the last three operating cycles of the machine. When disconnected from the plungers 110, the slides 208, together with the tack-pulling rakes 200 carried thereby, are held in elevated positions, see Fig. 5, by means of coil springs 282, stretched between pins 284 carried by the brackets 210 and the lower ends of these slides, Fig. 2.

In addition to the up-and-down movements which are imparted to the tack-pulling rakes 200, in the manner just explained, these rakes are moved in directions extending laterally of the shoe bottom to facilitate their tack-pulling actions. Fixed to each of the overlaying members 108 is a pin 300 that projects into a slot 302 formed in one end of a plunger 304 which is slidable in a guideway formed in a plate 306, secured to the housing 100, Fig. 3. Interposed between this pin and an abutment member 308, fixed to each of the plungers 304, is a compression spring 310. Adjacent to its lower end, each of the arms 204 is formed with an angularly disposed camming surface 312, and these arms are swung about their pivotal connections on the slides 208, to hold these camming surfaces against rounded ends 314 on the plungers 304, by means of coil springs 316, Figs. 2 and 3.

The tack-pulling devices which have just been described operate in the following manner. As already explained, the slides 208 are connected to the plungers 110, which operate the wire-feeding mechanisms, as the pattern camshaft 266 is rotated during the latter part of the ninth operating cycle of the machine. These plungers are reciprocated once during each operating cycle, moving upwardly on a return stroke just after the overlaying members 108 complete their movements toward the insole rib and as the fastening is being driven, and moving downwardly to effect feeding of the wire just after these overlaying members have been withdrawn, during the last

half of the operating cycle. Thus, as the shoe is fed along between the ninth and tenth operating cycle, the slides 208 will be moved downwardly by the plungers 110 to bring the tack-pulling rakes 200 to positions corresponding to that illustrated in Fig. 3. Now, during the first half of the tenth operating cycle as the overlaying members are operated to wipe the lasting margin of the stock in over the insole to press it against the insole rib, the tack-pulling rakes will be swung inwardly over the bottom of the shoe by the action of the plungers 304 so that the fingers 214 of these rakes will engage any pulling over tacks "t" in that vicinity, see solid line position illustrated in Fig. 2 and the lower broken-line position of Fig. 3. Next, as the fastening is driven and as the plungers 110 move upwardly on their return strokes, these tack-pulling rakes will be elevated to positions corresponding to that illustrated by the upper broken-line position in Fig. 3, thus removing any tacks previously engaged thereby. During such upward movement of the tack-pulling rakes, the rounded ends 314 of the plungers 304 will travel along the camming surfaces 312 on the arms 204 thereby imparting a further component of movement to these rakes and causing them to follow, more or less, any inward deflection of the tacks as they are withdrawn from the last. As the operating cycle is completed, the tack-pulling rakes are returned to positions corresponding to that shown in solid lines in Fig. 3 by the action of the springs 316. The foregoing actions of the tack-pulling rakes are repeated during the eleventh and twelfth operating cycles of the machine and then, as the pattern cam shaft is rotated the twelfth time, following the last operating cycle, the cam roll 254 passes up rise 272 onto the dwell 268 of the cam 256 thus disconnecting the slides 208 from the wire-feeding plungers 110.

During the operation of the tack-pulling rakes 200, the finger 214 of each rake which strikes the stem of a tack will yield, relatively to the other fingers, as permitted by the cushion block 216, thereby causing the adjacent fingers to be inserted beneath the head of the tack, see Fig. 6. Hence, when the rakes are elevated, any tacks so engaged by the fingers 214 will be positively withdrawn. The yielding connection between the overlaying members 108 and the plungers 304, provided by the compression springs 316, prevent damage to the parts if, for any reason, the tack-pulling rakes are prevented from completing their inward movements together with the overlaying members. It will be apparent from Figs. 1 and 2 that the tack-pulling rakes 200 are located adjacent to, but slightly ahead of, the gripper jaws 104, 106 of the lasting units. Inasmuch as these tack-pulling rakes are first set into operation during the tenth operating cycle, while the lasting units are operating some distance to the rear of the tip line, and are operated also during the eleventh and twelfth operating cycles, they will effectively remove those pulling-over tacks which are located adjacent to, and on either side of, the tip line. Thus, the difficulties previously encountered as the result of the driving-in, or bending-over, of these tacks by the overlaying members are avoided.

Referring to Figs. 8 and 9 of the drawings, the gripper jaws 104, 106 of each of the two lasting units are closed, moved upwardly away from the bottom of the shoe to tension the upper materials, opened and then moved downwardly, during each operating cycle of the machine by means of

an actuating member 400 and these actuating members are reciprocated by means of mechanism, not shown, but which is the same as that disclosed in Lawson Patent No. 2,201,866. These actuating members each carry a pin 402 which passes through angularly disposed slots 404, 406 formed respectively in the gripper jaws 104, 106 and these jaws are pivotally connected by means of a pin 408. Extending upwardly from each of the jaws 104 is a rod 410 and these rods are engaged by friction devices, not shown, which cause the gripper jaws to be opened and closed in response to upward and downward movements of the actuating members. Also mounted on each of the pins 408 is a latch member 412 having a hook portion 414 and an operating arm 417. When the gripper jaws are opened, as a result of the downward movement of the pins 402 on the actuating members to the lower end of the angularly disposed slots 404, 406, the hook portion of each latch member is disposed somewhat above a shoulder 416 formed on its associated actuating member so that the latch member can be moved to latching position, see Fig. 8, by means of a link 418.

As is explained in the aforementioned Lawson patent, when the gripper jaws are returned to their lowermost position, Fig. 9, the operating arms 417 engages fixed stop pins 420, carried by the housings 100 of the lasting units, so that the latch members are swung away from the shoulders 416, and these pins are so disposed that the latch members are held in these positions until the shoulders 416 have been elevated above the hook portions 414 during the next upward movement of the actuating members. However, when the extent of downward movement of the actuating members is reduced, in the manner explained in the Lawson patent and under the control of a cam 254 on the pattern cam shaft (12, see Fig. 15 of the Lawson patent) the hook portions 414 of these latch members are permitted to latch over the shoulders 416 so that the jaws 104, 106 are elevated without closing on the upper materials. In the machine of the Lawson patent, the extent of downward movement of the actuating members is reduced and the gripper jaws rendered inoperative during the last two operating cycles of the machine, and for that purpose, the control cam 254 is provided with two low portions 300 and 302.

Still referring to the Lawson patent, it will be seen that the actuating members 400 are reciprocated by means of a cam on the operating shaft (10, Fig. 15 of Lawson) of the machine which operates through mechanism including a fulcrum 240 which, when the actuating members are moved upwardly, is supported by a spring, or springs 246, 256, and when the actuating members are moved downwardly, is positioned by the control cam 254 on the pattern cam shaft. Accordingly, the actual extent of upward movement which is imparted to the gripper jaws by the actuating members, after the jaws have closed on the upper materials, will vary depending upon the resistance offered by the upper materials. As the lasting operation approaches the tip line of the shoe, in which vicinity the upper materials have been previously tensioned, the resistance thereof to further tensioning increases and may become so great that the gripper jaws, after they have closed on the upper materials, can be moved upwardly only a very short distance.

or not at all. When such conditions are met during those operating cycles in which the subsequent downward movement of the actuating members 400 are reduced, the following difficulties may be experienced. If the gripper jaws cannot be moved upwardly at all, the subsequent decreased downward movements of the actuating members may not be sufficient to effect opening of the jaws and, during the next feeding movement of the jack, the upper materials still gripped by the gripper jaws will be distorted, or torn. Even if the jaws move upwardly a short distance and the decreased downward movement of the actuating members is sufficient to open the jaws, at least partially, it may not be enough to dispose the shoulders 416 thereon below the hook portions 414 of the latch members. Thus, the gripper jaws will be closed on the upper materials during the next operating cycle and conditions further aggravated.

The herein illustrated machine is provided with improved means for rendering the gripper jaws inoperative, during the last two (eleventh and twelfth) operating cycles, which avoids the aforementioned difficulties. Referring to Fig. 2 of the drawings, projecting upwardly from the rearwardly extending arms 238 of the bell-crank levers 234 are links 500 which are connected to arms 502. Each of these arms is secured to one end of a shaft 504 which extends through the housing of one of the lasting units and carries at its opposite end a second arm 506, Fig. 7. Each of the pins 420 is eccentrically disposed on the end of a shaft 508 which extends outwardly through housing 100, see Figs. 8 and 9, and has secured to it an arm 510, Fig. 7. Connected to each of these arms is a link 512 having in its upper end a slot 514 which receives a pin 516 mounted on one of the arms 506. Stretched between the lower end of each of the links 512 and one of the pins 516 is a tension spring 518. Each of these links is cut away to provide a shoulder 520 which is normally engaged by the hooked end 522 formed on one arm of a detent lever 524. Each of these detent levers is pivoted, by means of a stud 526, on a cam block 528 associated with the driver-operating parts of the fastening-inserting mechanism of one of the lasting units. The other arm 530 of each of these detent levers is formed with an end 532 which projects into the cam track 534 in the block 528. A coil spring 536, surrounding the stud 526, tends to rotate each of the detent levers in a direction to hold its hooked end 522 in engagement with the shoulder 520 on one of the links 512. As is explained in the patent to Robinson et al. No. 2,418,140, referred to above, the driver-operating parts of each of the fastening-inserting mechanisms includes a cam roll 538 which, during the operation of the fastening-inserting driver, is moved along the cam slot 534 from the position in which it is shown, Fig. 7, to the opposite end of this slot.

Referring to Fig. 1 of the drawings, a cam which corresponds to cam (254) of the Lawson patent and controls the extent of downward movement of the gripper jaw actuating members is indicated by the reference character 540. This cam, which is mounted on the pattern cam shaft 266, is provided with two dwell portions 542 and 544, a drop-off portion 546 and a rise 548. Cooperating with this cam is a cam roll 549 carried by a bell-crank lever 550, shown partially broken away, which is associated with the mechanism for changing the position of the gripper-

operating fulcrum (cf., bell-crank lever 252, Fig. 15 of Lawson No. 2,201,866).

The improved mechanism for rendering the gripper jaws inoperative functions in the following manner. When the bell-crank levers 234 are swung into positions corresponding to that illustrated in Fig. 4 of the drawings, as a result of the partial rotation of the pattern cam shaft 266 during the latter portion of the ninth operating cycle and in the manner explained above, each of the arms 506 is swung upwardly, see arrow Fig. 7, thereby stretching the springs 518 and causing the pins 516 to travel to the upper ends of the slots 514 in the links 512. Now, after the gripper jaws have been operated to seize and apply tension to the upper materials, during the first half of the tenth operating cycle of the machine, the fastening-inserting drivers are operated and the cam rolls 538 caused to travel along the cam tracks 534 and to strike the ends 532 of the detent levers 524, thereby releasing the links 512 for upward movement by the springs 518. As a result of this upward movement of these links the shafts 508 are rotated, by the arms 510, in directions corresponding to that indicated by the arrows in Figs. 8 and 9 so that the pins 420 are displaced downwardly from the positions shown in these figures. This occurs before the operating cam starts to impart downward movement to the gripper-actuating members during the tenth operating cycle.

Referring again to Fig. 1, the drop-off 546 on the cam 540 is so disposed that the cam roll on the bell-crank lever 550 remains on the dwell portion 542 until the latter half of the tenth operating cycle has been substantially completed. Hence, the fulcrum 240 of the gripper-operating mechanism is maintained in a position to cause the operating cam to impart complete downward movements to the actuating members 400 which is sufficient to open the gripper jaws regardless of how much upward movement had been previously imparted to these jaws. Just as soon as these jaws are thus opened, the latch members 412 are moved into latching position by the links 418, this being permitted even though the opening of the gripper jaws occurs when these jaws are in their lowermost positions, inasmuch as the pins 420 have been displaced downwardly, as already explained. Immediately thereafter, and just before the beginning of the eleventh operating cycle, the cam roll on the bell-crank lever 550 drops down onto the dwell 544 of the cam 540, thereby repositioning the gripper-operating fulcrum to a location in which the gripper-actuating members are moved upwardly away from the bottom of the shoe. As the actuating members are thus moved upwardly, the gripper jaws remain open due to the fact that the hook portions of the latch members are in engagement with the shoulders on the actuating members therein. The cam roll on the bell-crank lever 550 remains on the dwell portion 544 of the cam 540 during the eleventh operating cycle and also during the first half of the twelfth operating cycle. After the twelfth operating cycle has been substantially completed, the cam roll on the bell-crank lever 550 travels up the rise portion 548 and onto the dwell 542 of the cam 540. Thus, the gripper-operating fulcrum (240) is repositioned to cause a complete downward movement of the actuating members 400 during the first operating cycle after the machine is again started to last another shoe.

Having described the invention, what is claimed

as new and desired to secure by Letters Patent of the United States is:

1. A machine for operating on shoes having, in combination, a pair of devices for operating along the opposite sides of the bottom of a shoe, progressively, in a plurality of successive operating cycles, a member associated with each of said devices and operable to remove fastenings previously inserted into the shoe, in locations adjacent to the marginal edge of the shoe bottom, and mechanism for rendering said fastening-removing members operative during predetermined cycles of operation of said devices.

15 2. A machine for lasting shoes having, in combination, a pair of devices for working the upper materials over the bottom of a shoe and for securing said materials in lasted position, in different locations along the opposite sides of the bottom of the shoe, progressively, in a plurality of successive operating cycles, and a member associated with each of said devices and operable to remove fastenings previously inserted into the shoe, in locations adjacent to the marginal edge of the shoe bottom, during the operation of the machine.

20 3. A machine for lasting shoes having, in combination, a pair of devices for working the upper materials over the bottom of a shoe and for securing said materials in lasted position, in different locations along the opposite sides of the bottom of the shoe, progressively, in a plurality of successive operating cycles, a member associated with each of said devices and operable to remove fastenings previously inserted into the shoe, in locations adjacent to the marginal edge of the shoe bottom, and mechanism for rendering said fastening-removing devices operative during predetermined cycles of operation of said devices.

25 4. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively in a plurality of successive operating cycles, and a member associated with each of said devices for removing fastenings previously inserted into the shoe, in locations adjacent to the marginal edges of the shoe bottom, during the operation of the machine.

30 5. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, and mechanism for rendering said fastening-removing members operative during predetermined cycles of operation of said devices.

35 6. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, a member associated with each of said

devices and operable to remove fastenings previously inserted into the shoe, in locations adjacent to the marginal edges of the shoe bottom, and mechanism including a control cam for rendering said fastening-removing members operative during predetermined cycles of operation of said devices.

7. A machine for lasting shoes having, in combination, a pair of devices each including a gripper for tensioning the upper materials of a shoe and an overlaying member for working the lasting margin of the tensioned stock inwardly over, and for pressing it against the shoe bottom, in different locations along the opposite sides of the bottom of the shoe, progressively, in a plurality of successive operating cycles, and a member associated with each of said devices for removing fastenings previously inserted into the shoe, in locations adjacent to the marginal edges of the shoe bottom, during the operation of the machine.

8. A machine for lasting shoes having, in combination, a pair of devices each including a gripper for tensioning the upper materials of a shoe and an overlaying member for working the lasting margin of the tensioned stock inwardly over, and for pressing it against the shoe bottom, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, and mechanism for rendering said fastening-removing members operative during predetermined cycles of operation of said devices.

9. A machine for lasting shoes having, in combination, a pair of devices each including a gripper for tensioning the upper materials of a shoe and an overlaying member for working the lasting margin of the tensioned stock inwardly over, and for pressing it against the shoe bottom, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, and mechanism including a control cam for rendering said fastening-removing members operative during predetermined cycles of operation of said devices.

10. A machine for lasting shoes having, in combination, a pair of devices each comprising a gripper for tensioning the upper materials of a shoe, and a fastening-inserting mechanism for securing the lasting margin of the tensioned upper materials in lasted position, in different locations along the opposite sides of the bottom of the shoe, progressively, in a plurality of successive operating cycles, a member associated with each of said devices for removing fastenings previously inserted into the shoe, in locations adjacent to the marginal edges of the shoe bottom, and means for connecting said members for operation by the fastening-inserting mechanisms of said devices, during the operation of the machine.

11. A machine for lasting shoes having, in combination, a pair of devices each comprising a gripper for tensioning the upper materials of a shoe, and a fastening-inserting mechanism for securing the lasting margin of the tensioned upper materials in lasted position, in different locations along the opposite sides of the bottom of the shoe, of

the shoe, progressively, in a plurality of successive operating cycles, a member associated with each of said devices and operable to remove fastenings previously inserted into the shoe, in locations adjacent to the marginal edges of the shoe bottom, and mechanism for connecting said members for operation by the fastening-inserting mechanisms of said devices, during predetermined operating cycles of the devices.

12. A machine for lasting shoes having, in combination, a pair of devices each comprising a gripper for tensioning the upper materials of a shoe, and a fastening-inserting mechanism for securing the lasting margin of the tensioned upper materials in lasted position, in different locations along the opposite sides of the bottom of the shoe, progressively, in a plurality of successive operating cycles, a member associated with each of said devices and operable to remove fastenings previously inserted in the shoe, in locations adjacent to the marginal edges of the shoe bottom, and mechanism including a control cam for connecting said members for operation by the fastening-inserting mechanisms of said devices, during predetermined operating cycles of the devices.

13. A machine for lasting shoes having, in combination, a pair of devices each including a gripper for tensioning the upper materials of a shoe, and a fastening-inserting mechanism, including an overlaying member and means for feeding wire, for inserting wire fastenings to secure the lasted margin of the tensioned upper materials in lasted position, in different locations along the opposite sides of the bottom of the shoe, progressively, in a plurality of successive operating cycles, a tack-pulling member associated with each of said devices for removing tacks previously driven into the shoe, in locations adjacent to the marginal edges of the shoe bottom, and means for connecting said tack-pulling members for operation by the overlaying members and wire-feeding means of said fastener-inserting mechanisms, during the operation of the machine.

14. A machine for lasting shoes having, in combination, a pair of devices each including a gripper for tensioning the upper materials of a shoe, and a fastening-inserting mechanism, including an overlaying member and means for feeding wire, for inserting wire fastenings to secure the lasted margin of the tensioned upper materials in lasted position in different locations along the opposite sides of the bottom of the shoe, progressively, in a plurality of successive operating cycles, a tack-pulling member associated with each of said devices and operable to remove tacks previously driven into the shoe, in locations adjacent to the marginal edges of the shoe bottom, and mechanism for connecting said tack-pulling members for operation by the overlaying members and wire-feeding means of the fastener-inserting mechanisms, during predetermined operating cycles of said devices.

15. A machine for lasting shoes having, in combination, a pair of devices each including a gripper for tensioning the upper materials of a shoe, and a fastening-inserting mechanism, including an overlaying member and means for feeding wire, for inserting wire fastenings to secure the lasted margin of the tensioned upper materials in lasted position, in different locations along the opposite sides of the bottom of the shoe, progressively, in a plurality of successive operating cycles, a tack-pulling member associated with each of said devices and operable to remove tacks previously driven into the shoe, in locations adjacent to the marginal edges of the shoe bottom,

and mechanism including a control cam for connecting said tack-pulling members for operation by the overlaying members and wire-feeding means of the fastener-inserting mechanisms, during predetermined operating cycles of said devices.

16. A machine for lasting shoes having, in combination, a pair of devices each including a gripper for tensioning the upper materials of a shoe and fastening-inserting mechanism for securing the lasting margin of the tensioned upper in lasted position, in different locations along the opposite sides of the bottom of the shoe, progressively, in a plurality of successive operating cycles, means associated with each of said devices for rendering the gripper inoperative including a latch member and a stop pin for disengaging said latch member, in response to a predetermined extent of downward movement of the gripper, and mechanism for displacing said stop pins to positions in which said latch members are engaged to render the grippers inoperative, regardless of the extent of downward movement thereof.

17. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, means associated with each of said devices for rendering the gripper inoperative including a latch member and a stop pin for disengaging said latch member, in response to a predetermined extent of downward movement of the gripper, and mechanism, operative during predetermined operating cycles of said devices, for displacing said stop pins to positions in which said latch members are engaged to render the grippers inoperative, regardless of the extent of downward movement thereof.

18. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, each of said grippers comprising a pair of jaws, a vertically reciprocable actuating member operable to effect opening and closing of said jaws and heightwise movement thereof, relatively to the bottom of the shoe, power-operated means for reciprocating the actuating members, mechanism associated with the power-operated means for varying the extent of downward movement imparted to said actuating members, during predetermined operating cycles of said devices, latch members associated with the grippers and arranged to connect the actuating members to said grippers and thereby discontinue closing of the gripper jaws, stop pins carried by said devices for disconnecting the latch members to dis-

connect the grippers from the actuating members, regardless of the extent of downward movement imparted to said actuating members, said control cam being operable to reduce the extent of downward movement imparted to said actuating members only after said last-mentioned mechanism has displaced said stop pins.

19. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, each of said grippers comprising a pair of jaws, a vertically reciprocable actuating member operable to effect opening and closing of said jaws and heightwise movement thereof, relatively to the bottom of the shoe, power-operated means for reciprocating the actuating members, mechanism associated with the power-operated means for varying the extent of downward movement imparted to said actuating members, during predetermined operating cycles of said devices, latch members associated with the grippers and arranged to connect the actuating members to the gripper jaws, thereby to discontinue enclosing movements thereof, stop pins carried by said devices for disconnecting the latch members when maximum downward movements are imparted to said actuating members, and mechanism, operative during predetermined operating cycles of said devices, for displacing said stop pins to positions in which they are ineffective to disconnect the grippers from the actuating members, regardless of the extent of downward movement imparted to said actuating members, said control cam being operable to reduce the extent of downward movement imparted to said actuating members only after said last-mentioned mechanism has displaced said stop pins.

20. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, each of said grippers comprising a pair of jaws, a vertically reciprocable actuating member operable to effect opening and closing of said jaws and to impart thereto heightwise movements, relatively to the bottom of the shoe, power-operated means for reciprocating the actuating members, mechanism including a control cam for reducing the extent of downward movement imparted to said actuating members, during predetermined operating cycles of said devices, latch members associated with the grippers and arranged to connect the actuating members to said grippers and thereby discontinue closing of the gripper jaws, stop pins carried by said devices for operating the latch members to disconnect the grippers from the actuating members, when maximum downward movements are imparted to the actuating members, and mechanism for displacing said stop pins to positions in which they are ineffective to disconnect the grippers from the actuating members, regardless of the extent of downward movement imparted to said actuating members, said control cam being operable to reduce the extent of downward movement imparted to said actuating members only after said last-mentioned mechanism has displaced said stop pins.

21. A machine for lasting shoes having, in combination, a pair of devices each including a gripper for tensioning the upper materials of a shoe and a fastening-inserting mechanism for securing the lasting margin of the tensioned upper in lasted position, in different locations along the opposite sides of the bottom of the shoe, progressively, in a plurality of successive operating cycles, each of said grippers comprising a pair of jaws, a vertically reciprocable actuating member operable to effect opening and closing of said jaws and to impart thereto heightwise movements, relatively to the bottom of the shoe, power-operated means for reciprocating the ac-

tuating members, mechanism including a control cam for reducing the extent of downward movement imparted to said actuating members, during predetermined operating cycles of said devices, latch members associated with the grippers and arranged to connect the actuating members to said grippers and thereby discontinue closing of the gripper jaws, stop pins carried by said devices for operating the latch members to disconnect the grippers from said actuating members, when maximum downward movements are imparted to the actuating members, and mechanism, operative during predetermined operating cycles of said devices, for displacing said stop pins to positions in which they are ineffective to disconnect the grippers from the actuating members, regardless of the extent of downward movement imparted to said actuating members, said control cam being operable to reduce the extent of downward movement imparted to said actuating members only after said last-mentioned mechanism has displaced said stop pins.

22. A machine for lasting shoes having, in combination, a pair of devices each including a gripper for tensioning the upper materials of a shoe and a fastening-inserting mechanism for securing the lasting margin of the tensioned upper materials in lasted position, in different locations along the opposite sides of the bottom of the shoe, progressively, in a plurality of successive operating cycles, a member associated with each of said units for removing fastenings previously inserted into the shoe, in locations adjacent to the marginal edges of the shoe bottom, and mechanism for discontinuing the tensioning actions of said grippers and for rendering said fastening-removing members operative, during the operation of the machine.

23. A machine for lasting shoes having, in combination, a pair of devices each including a gripper for tensioning the upper materials of a shoe and a fastening-inserting mechanism for securing the lasting margin of the tensioned upper materials in lasted position, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, and mechanism for discontinuing the tensioning actions of said grippers and for rendering said fastening-removing members operative, during predetermined operating cycles of said devices.

24. A machine for lasting shoes having, in combination, a pair of devices each including a gripper for tensioning the upper materials of a shoe and a fastening-inserting mechanism for securing the lasting margin of the tensioned upper materials in lasted position, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, and mechanism including a control cam, for discontinuing the tensioning actions of said grippers and for rendering said

fastening-removing members operative, during predetermined operating cycles of said devices.

25. A machine for lasting shoes having, in combination, a pair of devices each including a gripper for tensioning the upper materials of a shoe and a fastening-inserting mechanism for securing the lasting margin of the tensioned stock in lasted position, in different locations along the opposite sides of the bottom of the shoe, progressively, in a plurality of successive operating cycles, a member associated with each of said devices and operable to remove fastenings previously inserted into the shoe, in locations adjacent to the marginal edges of the shoe bottom, means associated with each of said devices for rendering the gripper inoperative, including a latch member and a stop pin for disengaging said latch member in response to a predetermined maximum extent of downward movement of the gripper, mechanism for rendering said fastening-removing members operative, during predetermined operating cycles of said devices, and means controlled by the last-mentioned mechanism for displacing said stop pins to positions in which said latch members are engaged to render the grippers inoperative, regardless of the extent of downward movement thereof.

26. A machine for lasting shoes having, in combination, a pair of devices each including a gripper for tensioning the upper materials of a shoe and a fastening-inserting mechanism for securing the lasting margin of the tensioned stock in lasted position, in different locations along the opposite sides of the bottom of the shoe, progressively, in a plurality of successive operating cycles, each of said grippers comprising a pair of jaws, a vertically reciprocable actuating member operable to effect opening and closing of said jaws and to impart heightwise movement thereto, relatively to the bottom of the shoe, power-operated means for reciprocating said actuating members, mechanism associated with the power-operated means for varying the extent of downward movement imparted to said actuating members, during predetermined operating cycles of said devices, latch members associated with said grippers and arranged to connect the actuating members to the gripper jaws, thereby discontinuing closing movements thereof, stop pins carried by said devices for disconnecting said latch members when maximum movements are imparted to said actuating members, a member associated with each of said devices and operable to remove fastenings previously inserted into the shoe, mechanism for rendering said fastening-removing members operative during predetermined operating cycles of said devices, and means controlled by said last-mentioned mechanism for displacing said stop pins to positions in which the latch members connect the gripper jaws to said actuating members, regardless of the extent of downward movements thereof.
